STAND FOR POTTED PLANTS AND THE LIKE

Rosalie P. Burrell, Harrisburg, Pa. (368 N. Summit Ave., Apt. 204, Gaithersburg, Md. 20760)

Filed May 19, 1975, Ser. No. 578,393

Term of patent 14 years

Int. Cl. D6—02

U.S. Cl. D6—182

FIG. 1 is a perspective view of a stand for potted plants and the like showing my new design;

FIG. 2 is a top plan view thereof;

FIG. 3 is a front elevational view thereof;

FIG. 4 is a side elevational view thereof; and

FIG. 5 is a bottom plan view thereof.

I claim:

The ornamental design for a stand for potted plants and the like, as shown.
